[57] CLAIM

The ornamental design for combined leg and armrest
unit for a chair, as shown and described.

DESCRIPTION

FIG. 1 is a frontside perspective view of a combined leg
and armrest unit for a chair showing my new design;
FIG. 2 is a backside perspective view thereof;
FIG. 3 is a side elevational view thereof;
FIG. 4 is a front elevational view thereof; and
FIG. 5 is a top plan view thereof.

The undisclosed portion of the inner face of the leg is
conventionally smooth, uninterrupted and unadorned.
The broken lines illustrated in the drawings are not a
part of the design sought to be patented.
